UNITED STATES PATENT OFFICE.

ANDREW EPPLER, OF LYNN, MASSACHUSETTS, ASSIGNOR TO UNITED SHOE MACHINERY COMPANY, OF PATERSON, NEW JERSEY, A CORPORATION OF NEW JERSEY.

THREAD-WAXING DEVICE.

1,023,071.

Specification of Letters Patent.

Patented Apr. 9, 1912.

Application filed November 22, 1909. Serial No. 529,414.

To all whom it may concern:

Be it known that I, ANDREW EPPLER, a citizen of the United States, residing at Lynn, in the county of Essex and State of Massachusetts, have invented certain new and useful Improvements in Thread-Waxing Devices; and I do hereby declare the following to be a full, clear, and exact description of the invention, such as will enable others skilled in the art to which it appertains to make and use the same.

The present invention relates to thread waxing devices for use on wax thread sewing machines.

15 One of the objects of the present invention is to produce a thread waxing device having improved means for heating the wax.

20 Another object of the invention is to produce a thread waxing device having its various parts constructed and arranged in an improved manner so that access may be readily had to the device or devices which guide the thread through the wax.

25 With the above objects in view the present invention consists in the devices and combinations of devices, hereinafter described and claimed the advantages of which will be obvious to those skilled in the art from the following description.

30 The several features of the present invention will be clearly understood from an inspection of the accompanying drawing in which—

35 Figure 1 is a transverse section of a thread waxing device embodying the several features of the present invention in their preferred form, and Fig. 2 is a view in side elevation partly in section, of the thread waxing device illustrated in Fig. 1.

40 The wax pot of the thread waxing device illustrated in the drawing is indicated at 1 and is divided in the usual manner into two compartments by a perforated partition 2 whereby a receptacle for new unmelted wax is provided at the rear side of the pot. The wax pot is removably secured beneath a horizontal support 3 rigidly secured to the main frame of the machine, which support 45 forms a cover for the main portion of the pot. The means for removably securing the pot to the support 3 consist of threaded bolts 4 pivotally mounted upon ears projecting from the pot and extending upwardly 50 through open-ended slots in the support 3.

55 Winged nuts 5 are threaded upon the upper ends of the bolts and are arranged to bear against the upper side of the support 3. Normally the pot 1 is held in position on the support 3 in the manner indicated in Fig. 1. To allow the pot to be moved downwardly away from the support the nuts 5 are loosened and the bolts 4 are swung outwardly and downwardly as indicated in Fig. 2. The thread, indicated at 6 in the drawing, 60 passes through openings in the support 3 and is guided through the wax and held immersed therein by a guiding roll 7 mounted upon the lower end of a guide frame 8 projecting downwardly from the support 3. The thread guide 7 and its frame 8 are thus fixed with relation to the support 3 so that when the pot 1 is moved downwardly away from the support 3 the thread guide is removed from the wax and can be readily 65 inspected. Also at this time the guide can be readily threaded.

70 To heat the wax in the wax pot a steam pipe 9 is provided which passes vertically downward in a straight line completely 75 through the pot. At its upper end the pipe 9 is connected to a supply pipe 10 and at its lower end to a supply pipe 11. The pipe 9 being straight presents no bends or pockets to collect water of condensation and also 80 offers no obstruction to the upward and downward movements of the wax pot. The pipe 9 is completely surrounded by the wax and extends parallel and in close proximity 85 to the thread 6 so that it acts in an efficient 90 manner to melt the wax in proximity to the thread. This arrangement of the steam pipe 95 also avoids overheating and burning of the wax since the melted wax in proximity to the tube tends to flow outwardly toward the walls of the pot where it is cooled, the radiation of heat from the walls of the wax pot effectually preventing the wax from becoming overheated at all times. Preferably, and as illustrated in the drawing, the steam pipe 9 passes through a tube 12, the lower 100 end of which is secured in the bottom of the wax pot and the upper end of which extends above the level of the wax and is received in a recess in the lower surface of the support 3. Thus tube 12 prevents the wax from coming directly into contact with the steam pipe and avoids caking of the wax on the pipe. The tube 12 loosely surrounds the pipe 9 so as to provide an air space which 105 110

- aids in preventing overheating of the wax. Also the steam pipe 9 is preferably made of copper while the tube 12 is made of iron, for the reason that the conductivity of iron is less than that of copper and the iron serves to still further diminish the danger of excess heating of the wax particularly at points where the tube 12 may accidentally come in contact with the pipe.
10. While the waxing device is in use the wax in the pot is kept melted by the steam pipe 9. To enable the wax to be quickly melted when heat is first applied to the pot, an auxiliary heating device may be employed. In 15 the construction illustrated in the drawing an auxiliary heating device in the form of a steam pipe 13 is provided arranged parallel to the pipe 9 and connected in the same manner to the supply and return pipes 10 and 11. This pipe passes through a tube 14 similar in all respects to the tube 12. Near its lower end and outside of the wax pot, the pipe 13 is provided with a valve 15 by means of which communication may be 20 shut off between the pipe 13 and the pipe 11. When the valve 15 is closed water of condensation collects in the pipe 13 and thus the operation of the pipe as a heating device is discontinued. The lower end of the 25 guide frame 8 is provided with lateral projections 16 which fit quite closely against the tubes 12 and 14 so that the heat is transmitted directly from these tubes to the guide frame 8 and thread guide 7.
30. The preferred embodiment of the several features of the present invention having been thus described, what is claimed is:—
35. 1. A thread waxing device, having, in combination, a support, a thread guide 40 mounted thereon, a wax-pot mounted so as to be movable into or out of a position in which the thread is immersed in the wax, and a heating pipe passing through the wax-pot in a straight line and in the direction 45 of the movement of the pot.
2. A thread waxing device, having, in combination, a support, a thread guide mounted thereon, a wax-pot, a heating pipe passing vertically in a straight line through the wax-pot and means for supporting the 50 wax-pot so as to allow it to be moved longitudinally of the heating pipe into and out of a position in which the thread is immersed in the wax.
3. A thread waxing device, having, in 55 combination, a wax-pot, a heating pipe passing through the wax-pot and emerging therefrom below the level of the wax, a thread guide to guide the thread through the wax in the wax-pot, and a tube loosely 60 surrounding the heating pipe and attached to the pot at the point where the heating pipe emerges therefrom.
4. A thread waxing device, having, in combination, a support, a thread guide 65 mounted thereon, a wax-pot, a heating pipe passing vertically in a straight line through the wax-pot, a tube loosely surrounding the heating pipe and attached at its lower end to the bottom of the pot, the upper end of 70 said tube extending above the level of the wax, and means for supporting the wax-pot so as to permit it to be moved longitudinally of the heating pipe into or out of a position in which the thread is immersed in 75 the wax.
5. A thread waxing device, having, in combination, a support, a thread guide mounted thereon, a wax-pot, a plurality of 80 heating pipes passing in straight lines through the pot, a shut-off valve in one of the pipes, and means for supporting the wax-pot so as to permit it to be moved into or out of a position in which the thread is immersed in the wax.

ANDREW EPPLER.
